SAFETY SWITCH BOX

Filed Feb. 11, 1925

2 Sheets-Sheet 2

UNITED STATES PATENT OFFICE.

DAVID T. WADSWORTH, OF COLD SPRINGS, KENTUCKY, ASSIGNOR TO THE WADSWORTH ELECTRIC MANUFACTURING COMPANY, OF COVINGTON, KENTUCKY, A CORPORATION OF KENTUCKY.

SAFETY SWITCH BOX.

Application filed February 11, 1925. Serial No. 8,534.

To all whom it may concern:

Be it known that I, DAVID T. WADSWORTH, a citizen of the United States of America, and a resident of Cold Springs, in the 5 county of Campbell and State of Kentucky, have invented new and useful Improvements in a Safety Switch Box, of which the following is a specification.

An object of my invention is to provide a 10 safety switch box wherein the switch mechanism and lead in terminals are normally retained within a closed and sealed compartment, while the fuses and fuse sockets are mounted in a separate compartment to 15 which access may be had through an aperture controlled by a sliding panel.

Another object is to provide a device of 20 this type wherein the fuses and fuse sockets are accessible only when the switch is disconnected from the lead in lines or source of power.

Another object is to provide a locking 25 means for automatically locking the panel of the fuse compartment when the switch is closed and for releasing said panel when the switch is in an open or off position.

Another object is to provide a locking device for the purpose stated that will occupy 30 a minimum of useful space within the switch box.

Another object is to provide a locking device of this kind which is so arranged to relieve the normal wall structure and cover sealing means of any strain resulting from 35 an endeavor to operate the switch when the box is not in a condition of safety.

Another object is to provide an operating 40 mechanism for switch boxes of the type described which serves to open the switch and unlock the panel with a single movement of the operating mechanism and also to lock the panel and close the switch with a single movement thereof.

Another object is to provide a mechanism 45 operating as above described wherein the opening of the switch precedes the unlocking of the panel and wherein the locking of the panel takes place before the closing of the switch.

Another object is to provide an operating 50 mechanism of this type which opens the switch rapidly and thereby precludes excessive arcing.

These and other objects are attained by the means described herein and disclosed in 55 the accompanying drawings, in which:

Fig. 1 is a perspective view of a switch box having embodied therein the device of my invention and showing the switch and locking means in a closed position. 60

Fig. 2 is a fragmental perspective view of 65 the same showing the operating mechanism, switch and locking means in an open position.

Fig. 3 is a fragmental cross sectional view 70 taken on line 3—3 of Fig. 1.

Fig. 4 is a side view of the operating mechanism forming a detail of my invention.

Fig. 5 is an enlarged perspective view of 75 the parts forming details of my invention.

Fig. 6 is a fragmental front view of the 80 switch box of my invention, the lid being in a closed position.

The switch box 5 is provided with an 85 interior wall 6 which serves to divide the interior of said box into a switch compartment 7 and a fuse compartment 8. An insulating base or plate 9 of any suitable material such as slate, porcelain, fibre or the like 90 is secured to the interior face 10 of the rear wall of the box and extends into both compartments. Upon this insulating base or plate 9 are mounted the switch blades 11, lead in terminals 12, switch jaws 13, fuse 95 sockets 14 and lead out or load terminals 15 so that all portions of the mechanism which carry an electric current are well insulated from the switch box 5 and from one another. The switch blades 11 are suitably secured to an insulating switch bar 16

so that said blades may always be moved simultaneously about their pivotal mountings. The bar 16 carries a pair of perforate lugs 17 through which a U-shaped 100 actuating arm 18 extends. The actuating arm 18 has the free ends of its branches pivotally mounted on the side walls 19 and 20 of the box 5. From the foregoing and by reference to Fig. 1 it will be apparent 105 that as the actuating arm 18 is moved about its pivotal mountings, the insulating switch bar 16 will travel with the actuating arm 18 to move the switch blades 11 into and out of contact with the jaws 13. The operating mechanism indicated generally as 21,

is rotatably mounted about one pivotal mounting of the actuating arm 18 and comprises a flat disc like portion 22 having an upwardly extending peripheral flange 23 extending along a portion of its periphery and a second peripheral flange 24 extending along a diametrically opposed portion of its perimeter. The actuating arm 18, with its pivotal mounting concentric with that of the operating mechanism 21 extends between the ends 25 and 26 of the flanges 23 and 24 respectively so that the actuating arm 18 may have a limited independent pivotal movement between said ends 25 and 26 and is adapted to be actuated by the operating mechanism 21 when the ends 25 or 26 are moved against the arm 18. A suitable spring member 27 has its opposite ends anchored on the flange 23 and arm 18 respectively and serves to yieldingly retain said arm in abutment with the end 26 of flange 24. The flange 24 carries upon its outer curve surface a cam 28 having a cam face 29 at its one side and a second cam 30 having a cam face 31. The cams 28 and 30 bear an off set relation one to the other with the cam faces 29 and 31 forming an obliquely disposed way between them.

The interior wall 6 is provided with a slot 32 or aperture bounded upon its one side by a catch member 33 which is preferably integral with the wall 6 and formed from the material struck from the aperture 32. A locking plate 34 is pivotally mounted at 35 upon the upper face of the wall 6 and is adapted to be swung about its pivotal mounting 35 to open and close the aperture 32 in said wall. A pin 36 extends upwardly from the locking plate 34 and is adapted to extend between the cam faces 29 and 31 and to be moved from side to side by said faces as the operating mechanism is moved about its pivotal mounting. The movement of the plate 34 is limited by the catch member 33. The movement of the pin 36 by the cams 28 and 30 serves to rock the plate 34 about its pivotal mounting for opening and closing the aperture 32 in the interior wall 6. The switch box 5 is provided with a suitable hinged cover 37 having an enlarged opening 38 therein which may be closed by a panel 39 slidably mounted between suitable strips 40 having their edges spaced from the interior wall of the cover 37. The panel 39 is provided with an inwardly extending rib member 41. When the switch box is closed the cover member 37 may be locked and sealed in any desired manner to preclude unauthorized opening of the box. When the locking plate 34 is moved away from the aperture 32, the panel 39 may be slid upwardly, the projecting rib member 41 passing through the aperture 32 in the interior wall 6 thereby rendering the fuse compartment 8 accessible for removal or renewal of

fuses. A spring clamp 42 may be provided upon the interior wall of the cover 37 for retaining the sliding panel 39 in its raised or uppermost position. The cover 37 being closed and locked and the locking plate 34 on the wall 6 being open, the sliding panel 39 may be freely raised and lowered. At this time, however, the pin 36 is in the position shown in Fig. 2 and the actuating arm 18 is in abutment with the end 26 of the flange 24 and under the influence of the spring 27. Assuming that the panel 39 is in a raised position with the rib member 41 extending through the aperture 32 and that an operator has renewed the fuses in the switch on without first closing the panel compartment 8, he now attempts to throw 39. The handle member 43 which serves to rotatably actuate the operating mechanism 21 will be in a lowered position as shown in Fig. 2. The operator, endeavoring to close the switch, will push the handle 43 upwardly whereupon the cam face 31 of the cam 30 will strike the pin 36 which in turn will tend to move the plate 34 about its pivotal mounting 35 to close the aperture 32. Having failed to lower the panel 39, the rib 41 extending through the aperture 32 blocks any material movement of the plate 34 so that it is impossible to close the switch and the operator is at the same time warned that the switch box is not in proper condition. Any force which is now applied to the handle 43 will be resolved into a shearing action of the edge of the plate 34 against the rib 41 extending through the aperture and in this way the cover member 37 and the walls 19 and 20 are relieved of any possible stress incident to such force. Since switch boxes of the type described are almost universally constructed of comparatively light sheet metal, for example 16 gage sheet steel, the advantage of relieving the normal wall structures of the box of any strain will readily be apparent since the metal of which they are constructed is readily capable of being sprung. The operator will then lower the panel 39 which will carry the rib member 41 below the interior wall 6 so that the aperture 32 therein will be free of obstruction and the locking plate 34 may be free to swing about its pivotal mounting for closing the aperture 32. As the operator now moves the handle 43 upwardly the cam face 31 will move the pin 36 to one side and the locking plate 34 will be swung about its pivotal mounting in order to completely close and lock the aperture 32. The panel 39 is now locked against further opening but the contact of the switch blades 11 with the switch jaws 13 has not been made and the operator must further actuate the handle 43 in the same direction whereupon the ends of the switch blades 11 will finally seat in the jaws 13 and 180

the switch is closed and ready for duty. During the closing action of the operating mechanism the actuating arm 18 was at all times in engagement with the end 26 of the 5 flange 24. However, in opening the switch and subsequently unlocking the panel 39, the handle 43 is actuated downwardly thereby pulling the end 26 of the flange 24 away from the arm 18. The binding action of 10 the jaws 13 upon the switch blades serves to retain the switch in a closed position while the operating mechanism is being moved and the spring 27 is being tensioned. The actuating arm likewise remains station- 15 ary while the tension of the spring 27 is being built up. As soon as the end 25 of the flange 23 abuts the arm 18, further movement of the handle will serve to positively move the actuating arm with it. Thus fur- 20 ther movement of the operating mechanism releases the switch blades from the binding action of the jaws and pulls said blades from the jaws and upon such release the tension of the spring 27 upon the arm 18 25 rapidly removes the switch blades from the contact with the jaws, thereby avoiding the arcing which takes place when a switch tends to hang adjacent its jaws.

It should be noted that while the actuating of the handle 43 in either direction is effected by a simple movement that in reality the opening of the switch always precedes the unlocking of the panel 39 by virtue of the mechanism just described and that the locking of the panel 39 always precedes closing of the switch, and also as has been heretofore described that it is impossible to close the switch until the panel 39 has been lowered to shut off access to the 30 compartment 8. As will be readily apparent the upper end of the rib member 41 lies below the interior wall 6 when the box is closed and the panel 39 is in a lowered position and that when the locking plate 45 34 has assumed a position beneath the catch member 33, the upper end of the rib 41 will strike said locking plate thereby precluding the lifting of the panel 39.

What I claim is:

50 1. In a device of the class described the combination with a switch box of an apertured interior wall in the box for providing a pair of compartments therein, a cover member forming a closure for the box and having an aperture therein for providing access to one of the compartments, a panel 55 slidably mounted upon the cover member for closing the aperture therein, an elongated rib carried by the panel and adapted to pass through the aperture in the interior wall when the panel is moved along its 60 slidably mounting, and means mounted upon the interior wall and contained within the second compartment for closing the aperture 65 in said interior wall.

2. In a device of the class described the combination of a switch box having an apertured interior wall for providing a pair of compartments therein, a switch mounted in one of the compartments, an operating 70 mechanism for the switch mounted upon a side wall of said compartment, and operable from the exterior of the box, a cover for the box having an aperture therein providing access to the second compartment, a 75 sliding panel mounted on the cover for effecting a closure of the aperture therein, an elongated rib carried by the panel and adapted when the box is closed to be reciprocated through the aperture in the interior 80 wall when the panel is moved, a locking plate carried by the interior wall and disposed within the first mentioned compartment and adapted to close the aperture in the interior wall, and co-operating means 85 carried by the locking plate and operating mechanism for actuating said locking plate to close the aperture in the interior wall as the operating means are actuated to close the switch, the elongated rib on the panel precluding movement of the panel when the aperture in the interior wall is closed by the locking plate and precluding movement of the locking plate and operating mechanism 90 when the sliding panel is in an open position. 95

3. In a device of the class described the combination with a switch box having an apertured interior wall for providing a pair of noncommunicating compartments, of a 100 cover for the box having an aperture providing access to one of the compartments, a sliding panel mounted upon the cover and adapted to be raised and lowered upon its 105 slidable mounting for controlling access to the last mentioned compartment, an elongated rib carried by the panel and adapted to be reciprocated through the aperture in the interior wall as the panel is raised and lowered, a locking plate pivotally mounted upon the interior wall and adapted to be moved about its pivotal mounting for opening and closing the aperture in said interior wall, a pin extending from the locking 110 plate, and a rotatable operating mechanism comprising a flange and peripheral cams upon said flange for effecting movement of the pin whereby the locking plate is moved about its pivotal mounting. 115

4. In a locking mechanism for switch boxes the combination with an apertured wall, an integral catch member carried by said wall and positioned adjacent the aperture therein, a locking plate pivotally mounted upon the wall and adapted to be moved about its pivotal mounting for opening the aperture and for engaging the catch member for closing the aperture, a rib adapted to be reciprocated through the aperture 120 in the interior wall when the aperture 125 130 135 140 145 150 155 160 165 170 175 180

is open and to abut the locking plate when the aperture is closed, and means for moving the locking plate about its pivotal mounting.

5. In a device of the class described the combination with a switch box having a slotted interior wall therein for providing an upper and a lower compartment, of a pivotally mounted switch in the upper compartment, fuse sockets in the lower compartment, an operating mechanism mounted within the switch compartment and comprising a rotatable body, spaced transverse flanges carried by the body and peripheral
- 10 cams carried by one of the flanges, a pivotally mounted throw rod connected to the switch and extending between the spaced ends of the transverse flanges, a locking plate pivotally mounted upon the interior
- 15

wall adjacent the aperture therein, a pin 20 extending from the locking plate and abutting the cams, a cover for the box, a panel slidably mounted upon the cover, a rib mounted upon the panel and adapted to be reciprocated through the aperture as the 25 panel is slidably actuated upon the cover, and means for actuating the cams whereby the pin is moved to actuate the locking plate for opening and closing the aperture in the interior wall whereby to selectively 30 permit and preclude reciprocation of the rib through the aperture in the interior wall.

In testimony whereof, I have hereunto subscribed my name this 5th day of February, 1925.

DAVID T. WADSWORTH.
